CLAIM

The ornamental design for a corner connector, as shown and described.

DESCRIPTION

FIG. 1 is a perspective view showing my new design, comprising a corner connector;

FIG. 2 is a top plan view thereof;

FIG. 3 is a left side elevational view thereof;

FIG. 4 is a right side elevational view thereof;

FIG. 5 is a perspective view showing another embodiment of my new design, comprising a corner connector;

FIG. 6 is a top plan view thereof;

FIG. 7 is a left side elevational view thereof; and,

FIG. 8 is a right side elevational view thereof.

Portions of the corner connectors are shown in broken lines in FIGS. 1-8 for illustrative purposes only and form no part of the claimed design.
